UNITED STATES PATENT OFFICE.

LEO H. CORMIER, OF BROOKLYN, NEW YORK.

SPINDLE FOR MILLING-MACHINES AND LATHES.

1,222,934.

Specification of Letters Patent.

Patented Apr. 17, 1917.

Application filed October 10, 1916. Serial No. 124,894.

To all whom it may concern:

Be it known that I, LEO H. CORMIER, a citizen of the United States, and a resident of Brooklyn, in the county of Kings and State of New York, have invented a certain new and useful Improvement in Spindles for Milling-Machines and Lathes, of which the following is a specification.

The present invention relates to milling machines and lathes, and refers particularly to a novel spindle or shaft construction for mounting the milling cutter, and for holding small work to be turned in close proximity to the tool post.

An object of the present invention is to provide a spindle construction which will permit of the grinding of valves, and the truing of bores in a quick and economical manner, and which will greatly facilitate the use of the lathe for all of its ordinary uses.

It is the further aim of the present invention to provide a spindle possessing the above characteristics, and which will not alter the construction or arrangement of the other parts of the lathe; which will not interfere with any of the adjustments of the same; and which may be readily applied to lathes now in use.

Other objects and advantages of this invention, as well as the above, will be pointed out more clearly in the following detailed description of the present preferred embodiment of this invention, the same being disclosed in the accompanying drawings wherein:

Figure 1 is a longitudinal central sectional view taken through the head-stock of a milling machine or lathe, and showing the spindle of this invention applied thereto.

Fig. 2 is a transverse section taken on the line 2--2 of Fig. 1, and looking in the direction of the arrows indicated.

Fig. 3 is a fragmentary sectional view of the outer end of the spindle showing a piece of stock mounted thereon and adapted to be turned down.

Referring to this drawing, 10 designates the bearing or post of the head stock of a lathe in which a hollow horizontal shaft 11 is mounted to turn. The shaft 11 is driven in the usual manner by a pulley 12 having a graduated peripheral surface for receiving a drive belt, not shown. The inner end of the shaft 11 may be supported in any suitable bearing, preferably by the bearing

shown in Fig. 1, and which is described and set forth in detail in my co-pending application Serial Number 124,895 filed of even date herewith. In general, the bearing comprises an intermediate roller 13 about which are arranged a plurality of pinions or small rollers 14 which latter have bearings in a casing 15 which is suitably secured to the post 10. The inner end of the shaft 11 extends beyond the bearing and is provided with the usual face plate 16, the latter being preferably threaded upon the end of the shaft.

A spindle 17 is telescoped into the shaft 11 and is provided in its periphery with a plurality of longitudinally extending grooves 18. Collars 19 are fitted in the shaft 11 and are provided in their inner walls with transversely extending ribs adapted to fit in the grooves 18 of the spindle. The collars 19 are held from turning, and from longitudinal displacement in the shaft 11 by means of set screws 20 which are threaded through the sides of the shaft 11, and which engage in the collars 19. The collars are placed preferably toward the opposite ends of the shaft 11 so as to support the spindle and cause the latter to turn with the shaft.

The spindle 17 is adapted to be shifted longitudinally in the shaft 11, and the means for accomplishing this result is an elongated screw rod 21 which is threaded through the outer closed end 22 of the shaft. The inner end of the rod 21 is provided with a head 23 seated in a recess 24 at the outer end of the spindle 17. A plate 25 is detachably secured upon the outer end of the spindle and receives the adjacent end of the screw rod 21 therethrough, the rod turning freely through the plate. In this manner, the screw rod 21 is swiveled upon the end of the spindle. A hand wheel 25 is mounted on the outer end of the screw rod 21 and is preferably of hollow construction. A handle 27 is pivoted in one side of the wheel 25 and is normally held by a spring 28 within the wheel out of the way. The wheel 26 is also provided with a flange 29 which overlaps the adjacent end of the shaft 11 and slides thereon for housing and protecting the outer end of the screw rod 21. A set screw 30 is threaded through one side of the shaft 11 adjacent to the inner end thereof, and is adapted to engage in recesses 31 in the side of the spindle 17 to hold the latter when adjusted. The inner end of the spindle 17 is provided cen-

105

110

trally with an outwardly flaring bore adapted to receive a plug or center 32 therein, and has at the inner end of the bore a threaded counter-bore adapted to receive the threaded 5 projection 33 of the plug 32. As shown in Fig. 1, the plug 32 is preferably provided with a hollow split outer end adapted to receive a milling cutter 34, or the like, thereon. By using this plug or center 32 the 10 spindle 17 may be retracted by turning the threaded rod 21 to bind the milling cutter 34 against the face plate 16. The milling cutter may now be strapped or otherwise suitably secured to the face plate, and the 15 spindle 17 further retracted out of engagement with the milling cutter.

As shown in Fig. 3, the center or plug 32^a may be provided with a solid outer end externally threaded for the reception of a nut, 20 or other piece of stock thereon. In this instance, the plug 32^a is provided with an angularly faced head upon its outer end, as indicated at 35, by means of which the plug may be turned into tight engagement with 25 the spindle 17. The nut, indicated at 36, is preferably spaced from the adjacent face of the plate 16 by means of a loose bushing 37 which surrounds the plug or center 32^a and is adapted to be bound against the face plate 30 16 by retracting the spindle 17. In this manner, the nut 36 is held rigidly in position and when the shaft 11 is turned the nut is rotated so that it may be worked upon in the usual manner, the nut being supported 35 adjacent to the tool post.

When a chuck, or the like, is secured against the face plate 16, and the plug 32 is not required, the screw rod 21 may be rotated to retract the spindle 17 and draw the 40 plug 32 into the shaft 11 out of the way. The spindle 17 is adapted to have approximately a six-inch sliding movement so as to accommodate the spindle and the shaft to all of the various uses required in the operation of the lathe. It is preferable to locate the inner collar 19 at least one inch out of the plane of the bearing which supports the 45 shaft 11 so that the bearing may freely expand and contract.

50 It is of course understood that the parts of this device as above specifically described may be changed as to dimensions and form to suit varying conditions of lathes, without departing from the spirit of the invention, 55 such changes and modifications being restricted only by the scope of the following claims.

I claim:

1. In a lathe, the combination of a hollow 60 shaft provided with a face plate upon its inner end, a spindle slidably mounted in said hollow shaft and adapted to turn therewith, a tool or work-supporting plug detachably mounted in the inner end of the spindle and 65 adapted to be projected beyond the shaft

and to be withdrawn into the shaft, and means carried by the shaft for shifting said spindle therein.

2. In a lathe, the combination of a hollow shaft, a face plate arranged at one end of the shaft, a spindle slidably mounted in said hollow shaft and adapted to turn therewith, a tool or work-supporting plug detachably mounted upon the inner end of the spindle and adapted to be projected beyond the 70 shaft and through the face plate to receive the work and to be withdrawn into the shaft for binding the work against the face plate, and operating means connected to the spindle for shifting the same.

3. In a lathe, the combination of a hollow shaft, a face plate mounted upon the inner end of the shaft, a spindle to slide longitudinally in the shaft and to turn therewith, a detachable center mounted upon the inner end of the spindle and adapted to be projected thereby beyond the end of the shaft for supporting the work, a screw rod threaded through the outer end of said shaft and having swivel connection with the adjacent 80 end of said spindle, and means on the outer end of said rod for turning the same to retract the spindle and bind the work against the face plate.

4. In a lathe, the combination of a hollow shaft having a face plate upon its inner end, a work supporting spindle mounted in the shaft adapted for longitudinal movement therein and adapted to turn therewith, means for shifting the spindle longitudinally in the shaft to bind the work against the face plate, and a set screw carried by the shaft for engagement with the spindle to lock the same in adjusted position.

5. In a lathe, the combination of a hollow shaft having a face plate thereon, a collar fitted in said shaft and secured thereto, said collar being provided with an internal transversely extending rib, a spindle fitting in said shaft provided with a longitudinally extending groove in its periphery for the reception of said rib whereby said spindle is permitted to move longitudinally in the shaft and is held for rotation therewith, and a tool or work support mounted on the projecting end of the spindle to bind the work against the face plate upon the retraction of the spindle.

6. In a lathe, the combination of a hollow shaft having a face plate, a spindle mounted in the shaft and provided with longitudinally extending grooves in its periphery, collars secured in the shaft provided with internal transversely extending ribs adapted to engage in said grooves and hold the 125 spindle for rotation with the shaft, adjusting means mounted on the outer end of the shaft and engaging the spindle to shift the same longitudinally, and a center carried upon the inner end of the said spindle for 130

supporting tools or the work, and adapted to be projected beyond the inner end of the shaft and to be retracted into the same by the shifting of said spindle to bind the work 5 against the face plate.

7. In a lathe, the combination of a hollow shaft having a face plate, a work supporting spindle mounted to move longitudinally in the shaft for binding the work against the 10 face plate and to turn therewith, a screw rod threaded through the outer end of said shaft

and having swivel connection with the adjacent end of said spindle, a hollow wheel mounted on the outer end of said screw rod, a handle pivotally mounted in one side of 15 the wheel and adapted to be swung outwardly for engagement by the hand to turn the wheel and adjust the spindle, and a spring carried by the wheel and engaging said handle to normally retract the same.

LEO H. CORMIER.
